LOCALIZED BLOW DISTRIBUTING
FOOTBALL HEADGUARD

James P. Taylor, Brooklyn, N. Y.

Application November 1, 1932, Serial No. 640,595

3 Claims. (Cl. 2-3)

This invention relates to body protectors of the type employed for protecting participants in violent games, such as football.

The object of the invention is to prevent the injurious effects to the body of either an extremely localized force from a blow or the sudden application to a part of the body itself of the entire force of a blow, although the same may be distributed over a large area. Stated differently, the principal object of the invention is to provide first for a shock absorbing local yielding in response to a blow, then the distribution of the force of the blow over a localized area of substantial extent, and then for the shock absorption of the said locally distributed force.

In carrying out my invention, I have found it particularly applicable to the protection of the head of football players and have found that a satisfactory embodiment may be fabricated functionally out of three parts; an outer layer, relatively thin, of resilient elastic material such as foam or sponge rubber, a thicker inner layer of the same foam or sponge rubber, and intermediate the two layers, bridges preferably discontinuous and out of contact with one another of strong, stiff material such as cane or wood.

In completing a preferred embodiment, the outer layer or wall of sponge rubber is protected on its exterior by means of a sheet of soft rubber, and I prefer to overlie or bridge the bridge pieces with a sheet of chamois and to protect the head engaging surface of the formation by means of an inner sheet of soft rubber. All the parts may be cemented or vulcanized together and the helmet may vary in contour and size to fit different heads and to accommodate more or less parts of the skull to be protected. Ear guards may be present if desired.

Particularly, my invention avoids the ineffective protection from such helmets as are constructed on the principle of employing a complete substantially non-resilient shell of sole leather or other stiff material provided with interior padding. I prefer to provide for the actual absorption of a blow as much as possible before a part of the human being is obliged to receive it, and particularly in connection with the head, it is an object to relieve the neck of the player from the usual sharp snapping action occasioned by the use of a shell type of helmet which imparts a snap to the neck in response to a substantial force before the player realizes he must resist a force. In my construction it is important that I provide an initial yielding which

is imparted by the outer cushion of soft rubber so that during the interval of the compression of this outer layer the player is warned and has time to prepare for the next snapping force which, with the use of my helmet, is never so great as with those heretofore provided. After the warning, my helmet insures a distribution of any localized force over a sufficiently great local area to prevent local injury such as skull fracture, but at the same time, limits the area of distribution and enables the shock absorbing inner layer to function actually to absorb a large amount of the force before the natural inertia of the body part tends to be overcome which must be overcome before the next snapping action commences.

My claims are directed to an illustrative embodiment of my invention described in the following specification in connection with the accompanying drawings, but solely for purposes of illustration and not limitation.

Fig. 1 is a perspective view of a football helmet embodying my invention and showing some of the interior construction in dotted lines; Fig. 2 is a similar front elevation; Fig. 3 is a horizontal section through the helmet; and Fig. 4 is an enlarged cross-section through the protective wall of the helmet.

In the drawings, a complete helmet A having ear guards B and B' is illustrated as provided with the usual chin strap 1. In the construction of my protector, the functioning features are best brought out by reference to the enlarged cross-section of Fig. 4 which is typical of my invention whatever the locality to be protected.

In this construction, the outside is preferably protected by a thin sheet of skin rubber 2 overlying and cemented to a sheet of chamois skin 3. The chamois skin imparts the necessary strength to prevent tearing from rough usage and protects the outer shock absorbing layer of sponge rubber 4 which is spaced apart from a thick inner layer of sponge rubber 5. Between these two layers of sponge rubber are separated discontinuous strips or bridges of cane 7 which are tied together or bridged by a sheet of chamois 8 cemented to the bridges. If desired, the spaces between the bridges 7 may be filled with sponge rubber 9 which functionally has the most usefulness in maintaining the spacing of the bridges and preserving the smooth outer contour for the helmet. The body contacting face of the wall is preferably covered with an inner sheet of skin rubber 10 cemented to the sponge rubber layer 5. Ventilating perforations 11 are

punched through the wall at localities between bridges 7. The drawings show the bridges 7 arranged in five major groups: one is the double side by side row extending from ear to ear over 5 the cranium and indicated collectively by 7A; another is the frontal group 7B in which the bridges run substantially vertically; another is the group 7C top frontal; another are the two horizontal rows 7D at the rear of the skull; and 10 the last group are the vertical bridges in group 7E for the ear guards B and B'.

Where the bridges overlie a decidedly curved portion of the part of the body to be protected, they are bent and permanently set to approximate 15 the elements of the contour which they overlie. This may be done by steaming and drying as is well known in the cane and wood working art.

As a result of my construction, the entire protector is lighter in weight than those heretofore provided and differs from all others in protecting against the extreme localizing of a blow and against the sudden imparting of the entire force of the blow to the whole head. On the reception 20 of a blow, the outer skin rubber and chamois prevents tearing and the immediately inner relatively thin layer of sponge rubber yields throughout the entire area of the blow with, however, a slight spreading of the force. When the yielding 25 imparted by the blow reaches the locality of the bridges 7, a substantial spreading of the force takes place which, however, is nevertheless still maintained local relatively to the entire helmet and the yielding of the inner layer 5 of sponge 30 rubber actually absorbs a large part of the blow before it is distributed over a sufficiently large area of the skull to prevent concussion. In no case is there a stiff outer shell which moves as a whole to impart a sudden terrific force to the 35 entire head of the type many times resulting in the breaking of the neck. Sufficient warning 40 sufficiently early is imparted to the wearer of my protector during the time that it takes for the outer layer of sponge rubber to yield for the 45 wearer to prepare to resist against neck fracture and thereafter is protection against too great localizing of the blow, and the absorption of a large part of its force takes place.

An important feature of my construction is

that after each blow the parts resume their initial normal position ready to receive another blow and function over again. The inner material in my construction is reduced to a minimum and the entire guard may be washed to maintain 5 its sanitary condition. In fact, it may be immersed in water without absorbing water, and in general, provides better protection than heretofore with less weight and with fewer unpleasant 10 features.

What I claim and desire to secure by United States Letters Patent is:

1. In a protective head covering, a locally shock absorbing helmet for protectively covering the skull, comprising an outer wall of material which is resilient and elastic both locally and throughout its extent, such as foam rubber; an inner wall of substantial thickness, also of material resilient and elastic, both locally and throughout its extent, such as sponge or foam 20 rubber; and intermediate said walls, spaced discontinuous force distributing bridges in the form of bars of stiff material, the whole functioning in response to a localized blow first locally to yield with a partial shock absorbing action, then 25 to locally distribute the force of the blow over an increased, but at the same time localized, area and then to yield to the locally distributed force with a shock absorbing function.
2. In a protector for a part of the body, an 30 inner wall of substantial thickness of shock absorbing resilient material; a plurality of intermediate discontinuous bridges of stiff material each of short length relatively to the size of the entire protector for locally distributing the force 35 of a blow; and an outer layer of shock absorbing resilient material, said protector being flexible except along the length of each short bridge.
3. In a protector for a part of the body, a composite protective pad comprising an outer protective sheet, then a layer of resilient shock absorbing material such as sponge rubber, then a bridging shield, then stiff spaced bridges of stiff material contacting with said bridging shield; an inner layer of substantial thickness of shock absorbing resilient material acted upon by said 45 bridges and an inner protective sheet for said resilient layer.

JAMES P. TAYLOR.
